UNITED STATES PATENT OFFICE.

WILLIAM SANDOW, OF KANSAS CITY, MISSOURI.

EXERCISING DEVICE.

Application filed May 1, 1926. Serial No. 106,068.

This invention aims to provide an exercising device adapted to be used by wrestlers and others, to strengthen the arm for the performance of that operation which consists in compressing the head of an opponent against the body of the operator, and thereby to acquire a strangle hold.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Figure 1 shows in top plan, a device constructed in accordance with the invention;

Figure 2 is a section on the line 2—2 of Figure 1;

Figure 3 is a section on the line 3—3 of Figure 2.

The device forming the subject matter of this application is made up of two members 1 which cooperate to approximate the human head in shape. The members 1 may be made of wood or any other suitable material. They taper, as at 2, from their upper to their lower ends, and have smooth outer side surfaces, portions of which are convexed, as at 3, both longitudinally and transversely. Because the external surfaces of the article are smooth, as above described, additional difficulty will be experienced in holding it, and the strength and skill of the person using the device, will be improved accordingly.

The members 1 have parallel inner surfaces 4 and the said members are supplied on their inner sides with seats 5 receiving

the ends of compression springs 6. The means for limiting the movement of the members 1, away from each other, under the action of the springs 6, may be of any desired form. In the present embodiment of the invention, but not of necessity, flexible strips 7 are provided for the purpose specified, the members 1 having flat end surfaces 8 to which the ends of the flexible strips 5 are attached by securing elements 9.

The operator holds the device between his arm and his body, and attempts to press the members 1 together, against the action of the springs 6. The device, obviously, will give the necessary exercise, and promote strength, in the way of acquiring a strangle hold.

What is claimed is:

1. A device of the class described adapted for use between the body and the arm of an operator, and, made up of two members which cooperate to approximate the human head in shape and size, whereby the arm will receive the same sort of exercise as that obtained when a human head is gripped between the arm and the body of the operator, the said members tapering from their upper to their lower ends and having smooth outer side surfaces, portions of which are convexed both longitudinally and transversely, spring means for holding said members spaced apart, and mechanism for limiting the separation of said members under the action of the spring means.

2. A device of the class described, constructed as set forth in claim 1, and further characterized by the fact that said mechanism embodies flexible strips located at the ends of the said members, the ends of the strips being connected to the ends of the said members.

In testimony that I claim the foregoing as my own, I have hereto affixed my signature.

WILLIAM SANDOW.
